his ATTORNEY

UNITED STATES PATENT OFFICE.

GEORGE W. KELLOGG, OF ROCHESTER, NEW YORK.

PUMP.

1,357,402.

Specification of Letters Patent. Patented Nov. 2, 1920.

Application filed December 4, 1919. Serial No. 342,419.

To all whom it may concern:

Be it known that I, GEORGE W. KELLOGG, a citizen of the United States of America, residing at Rochester, in the county of Monroe and State of New York, have invented certain new and useful Improvements in Pumps, of which the following is a specification.

My invention relates to pumps of the multiple cylinder type, and is particularly adapted to three cylinder hand pumps, although it is also applicable to power pumps and to structures involving more than three cylinders.

15 The purpose of the invention is to provide a practical construction, with parts so constructed as to make it possible to manufacture and assemble at a minimum expense. A further purpose of the improvement is to afford a mechanism which is extremely simple, having the fewest possible number of parts, and also possessing a high degree of operating efficiency.

25 The manner in which these and other purposes are accomplished will be apparent from the following detailed description, in conjunction with the accompanying drawing, the novel features being clearly pointed out in the claims at the end of the specification.

30 The drawing is a sectional view, illustrating a practical embodiment of my improvements.

The drawing illustrates a hand pump of 35 three cylinder type, but it is to be understood that the invention is not limited by this particular disclosure, and my improvements can be applied to other types and forms of pumps as well, and the present disclosure is intended merely to illustrate one instance of a practical application of the invention.

Referring more particularly to the drawing, A designates a central cylinder and B and B' are outer cylinders, disposed on opposite sides of the central cylinder A. These several cylinders are mounted upon a base C, and to this end, the base is provided with integral extensions D, D', which form 50 pockets to receive the lower ends of the several cylinders.

Coöoperating with the upper ends of cylinders B, B', is a head E which is prefer-

ably integral and provided with a central opening to permit it to pass over the central cylinder A. Suitable packing material is arranged about the upper cylinders B, B' and the adjacent surfaces of the head E, and in order to hold the several parts in their proper assembled relationship, securing means are provided which coöperate with the central cylinder A and with the head E and base C, said securing means acting to retain the central and also the outer cylinders in engagement with the base and the head.

To accomplish this, the central pocket of the base C, which is formed by the projection D', is threaded interiorly and the lower end of the central cylinder A is correspondingly threaded to engage the pocket and hold the central cylinder A tightly engaged with the base. The outer cylinders B, B' fit loosely into the corresponding pockets of the base, and are held in the following manner. The upper end of the central cylinder A is also threaded exteriorly to receive a correspondingly threaded cap F and the cap F engages the upper surface of the head E. Thus, the cap F forces the head E tightly against the outer cylinders B, B' into tight engagement with their pockets of the base C, the central cylinder being held tightly engaged with the base by its threaded connection already described. It will be seen, therefore, that after the central cylinder is secured to the base by its threaded connection, or any other suitable instrumentality, the remaining cylinders are held in place with the head tightly engaged thereon by the cap F. While this particular means is an extremely simple and practical way of assembling, other devices can be used which will accomplish the purpose with equal effectiveness.

The central cylinder A, is provided in its wall with the opening a, as usual in this general type of pump and the integral head E has provided therein passages b which establish communication between the openings a in the central cylinder and the upper ends of the outer cylinders B, B'. Air enters the outer cylinders through the openings c, passing around pistons G, and is compressed by the latter and forced into the central cylinder, during the upward

stroke of the handle H. Upon the down stroke, the air is forced out through the opening c by the central piston d.

In order to maintain a tight connection 5 between the central cylinder and the head, at the lower side of the latter, there is provided a packing d which is positioned against the under surface of the head surrounding the central cylinder, and the packing 10 d is held tightly against the head by means of a collar e threaded upon the central cylinder A.

While I have described the invention with 15 reference to a particular embodiment, the novel construction may be variously modified and changed without departing from the underlying features of the improvements, and this application is intended to 20 cover any such constructions as may come within the underlying spirit of the invention, and the scope of the following claims.

I claim:

1. A pump comprising a central cylinder and outer cylinders, a piston movable in 25 each of said cylinders, a head engaging the upper ends of the outer cylinders, said head having an opening permitting it to pass over the central cylinder and embodying means establishing communication between the inner and outer cylinders, and a cap threaded 30 on the central cylinder for closing it, said cap having engagement with said head and acting to retain the head against the ends of the outer cylinders.

2. A pump comprising a central cylinder and outer cylinders, a piston movable in 40 each of said cylinders, a base which engages the ends of said cylinders and forms the bottoms thereof, a head engaging the opposite ends of the outer cylinders and embodying means establishing communication between the inner and outer cylinders, said head having an opening permitting it to pass over the central cylinder, and means co-operating 45 with the central cylinder and with said base and head and acting to retain all the cylinders in engagement with the base and head.

3. A pump comprising a central cylinder and outer cylinders, a piston movable in 50 each of said cylinders, a base having integral extensions forming pockets to receive the ends of said cylinders, the central cylinder having threaded engagement with the base, an integral head engaging the opposite ends 55 of the outer cylinders and embodying means establishing communication between the inner and outer cylinders, said head having an opening permitting it to pass over the central cylinder, and means co-operating 60 with the central cylinder and head for holding the head engaged with the ends of the outer cylinders.

4. A pump comprising a central cylinder and outer cylinders, a piston movable in 65 each of said cylinders, a base having in-

tegral extensions forming pockets which receive the ends of the cylinders, the central cylinder having threaded engagement with the base, an integral head engaging the opposite ends of the outer cylinders and embodying means establishing communication between the inner and outer cylinders, said head having an opening permitting it to pass over the central cylinder, and a cap 70 threaded upon the central cylinder in engagement with the head and acting to close the cylinder and also retain the head against the ends of the outer cylinders.

5. A pump comprising a central cylinder and outer cylinders, a base having integral 80 extensions forming pockets which receive the ends of the cylinders, securing means acting to hold the central cylinder engaged with said base, the central cylinder having openings in its wall, an integral head having an opening permitting it to pass over the central cylinder, said head having engagement with the ends of the outer cylinders and provided with passages affording 85 communication between the outer cylinders and said openings in the wall of the central cylinder, and a cap in threaded engagement with the central cylinder and acting to retain the head against the outer cylinders.

6. A pump comprising a central cylinder 95 and outer cylinders, a base having integral extensions forming pockets which receive the ends of said cylinders, the central cylinder having threaded engagement with the base, an integral head engaging the opposite 100 ends of the cylinders and having an opening permitting it to pass over the central cylinder, said central cylinder having openings in its wall, and the head having passages affording communication between the outer 105 cylinders and the openings in the wall of the central cylinder, a cap having threaded engagement with the central cylinder and acting to retain the head against the ends of the outer cylinders, a packing positioned 110 around the central cylinder and located adjacent to the under surface of the head, and a collar having threaded engagement with the central cylinder and acting to retain said packing against the head.

7. A pump comprising a central cylinder and outer cylinders, a piston movable in each of said cylinders, a base which receives the lower ends of the cylinders, securing means acting to hold the central cylinder engaged 120 with said base, an integral head having an opening permitting it to pass over the central cylinder and embodying means establishing communication between said inner and outer cylinders, said head engaging the 125 upper ends of the outer cylinders, and a cap in threaded engagement with the central cylinder for closing it, said cap acting to retain said head against the outer cylinders.

8. A pump comprising a central cylinder 130

and outer cylinders, a piston movable in each of said cylinders, an integral head having an opening permitting it to pass over the central cylinder, said head engaging the 5 upper ends of the outer cylinders and having passages establishing communication between the central cylinder and the outer

cylinders, and a cap in threaded engagement with the central cylinder for closing the same.

In witness whereof, I have hereunto signed my name.

GEORGE W. KELLOGG.
